UNITED STATES PATENT OFFICE.

FRANK S. FROST AND ROBERT B. DUTCH, OF CHICAGO, ILLINOIS.

DESIGN FOR A DIRECTORY-STAND OR SIMILAR ARTICLE.

SPECIFICATION forming part of Design No. 31,524, dated September 19, 1899.

Application filed June 24, 1899. Serial No. 721,781. Term of patent 7 years.

To all whom it may concern:

Be it known that we, FRANK S. FROST and ROBERT B. DUTCH, citizens of the United States of America, residing in Chicago, in the county of Cook and State of Illinois, have 5 invented and produced a new and original Design for Directory-Stands, of which the following is a specification, reference being had to the accompanying drawings, forming part 10 hereof.

Figure 1 is a plan view of a directory-stand, showing our new design. Fig. 2 is an elevation.

As shown in the drawings, the leading or 15 material feature of our design consists of a central rectangular figure A and a border surrounding the same, worked on the top of the stand, such border comprising ribs or moldings B and rectangular panels C, the panels 20 being inclosed by the ribs and said several

figures being in relief and laterally arranged, as shown in Fig. 1 of the drawings. The ribs and panels are raised above the level of the central figure, the panels having less projection than the ribs. The outer ribs are flush 25 with the edges of the top and unite therewith as a portion of the edge finish or ornament.

It is obvious that this design is also applicable to tables or other similar articles having a rectangular top.

Having thus described our invention, what we claim, and desire to secure by Letters Patent, is—

The design for a directory-stand or similar article herein shown and described.

FRANK S. FROST.
ROBERT B. DUTCH.
